UNITED STATES PATENT OFFICE.

NATHANIEL J. ROGERS, OF TUSCALOOSA, ALABAMA, ASSIGNOR OF ONE-HALF TO
JAKE T. NEWBY, OF JACKSON, TENNESSEE.

PACKING-GUARD FOR JOURNAL-BOXES.

1,090,414.

Specification of Letters Patent. Patented Mar. 17, 1914.

Application filed April 26, 1913. Serial No. 763,799.

To all whom it may concern:

Be it known that I, NATHANIEL J. ROGERS, a citizen of the United States, residing at Tuscaloosa, in the county of Tuscaloosa and 5 State of Alabama, have invented certain new and useful Improvements in Packing-Guards for Journal-Boxes, of which the following is a specification.

This invention relates to an improvement 10 in packing holders for journal boxes.

The primary object of the invention is to provide a device disposed to be inserted within the journal boxes of railway cars, the device being maintained against displacement 15 by the weight of the car.

A further object of the invention is to provide a packing retaining means which will prevent the removal of the packing from the box until the car is raised, the construction being such that the packing may 20 be inspected and lubricated without removing the device.

For a full understanding of the invention, reference is to be had to the following 25 description and accompanying drawings, in which:—

Figure 1 is a sectional view of the journal box with the guard arranged therein; Fig. 2 is a perspective view of the form of 30 guard shown in Fig. 1; Fig. 3 is a perspective view of a slightly modified form of guard; Fig. 4 is a perspective view of a further modification; and Fig. 5 is a perspective view of a still further modified form.

Corresponding and like parts are referred 35 to in the following description and indicated in all the views of the accompanying drawings by the same reference characters.

In the drawings, 10 designates the journal 40 box, which is of the usual construction, and which receives the journal 11. The usual brass 12 is supported within the box and rests on the journal, the wedge member 13 contacting with said brass. The weight 45 of the car, which is disposed on the box, maintains the wedge member in contact with the brass, forcing it into engagement with the bearing. The construction thus far described is that of the usual form of journal 50 box, and the present invention broadly contemplates the provision of a member formed with a portion interposed between the wedge and the box whereby it is maintained against displacement by the weight of the car, the 55 member being provided with a guard or

shield which prevents the removal of the packing through the opening in the box.

In the preferred embodiment of my invention, this guard consists of the top plate 14 comprising a contracted neck portion 15 60 and the extensions 16. The packing retaining member is disposed at right angles to the plate 14, and is preferably formed integral therewith. This member consists of a sheet of material divided throughout the 65 greater portion of its length to provide spaced parallel retaining arms 17. These arms are formed with a plurality of inwardly disposed teeth 18 on each of their edges, and the connecting base portion 19 is 70 also formed with a plurality of teeth 20 which are inwardly disposed. When the car is raised, the plate 14 is inserted between the wedge 13 and the top of the box and the spaced arms 17 are disposed in front of 75 the opening 21 of the box, thus forming a shield which prevents the removal of the packing or waste 22 through the opening, the base portion 19 which connects the arms 17 contacting with the packing and preventing its displacement.

It will be noted that while the packing is prevented from being removed through the opening 21, it may be viewed through said opening and oil supplied to the same. The 85 box may be lubricated and inspected without the packing being supported where it may be removed without raising the car. Thus unauthorized persons are prevented from removing the packing or waste, thereby saying the same and, at the same time, maintaining sufficient packing within the box to prevent the journal from heating or cutting, as well as the wearing of the brasses. 90 It will also be noted that the lower portion 95 19 is so arranged as to maintain the packing in place, there being less packing needed when a device of this character is used than where the packing is permitted to work from beneath the journal. The top plate of 100 the guard may be either secured in place by being inserted over the wedge member, or it may be formed integral with said wedge member, it being noted that any suitable means of securing the top plate may be 105 used whereby the weight of the car will prevent the displacement of the plate.

While the preferred construction is illustrated in Figs. 1 and 2 of the drawing, the guard may be formed as illustrated in Fig. 110

3, consisting of the top plate 23 formed with the guard 24, the edge of which is toothed, and the body portion of which is slotted to permit of the insertion of oil and to allow 5 the packing to be inspected.

In the form shown in Fig. 4, the guard plate 25, which is formed integral with the plate on which the box rests, has a serrated edge 26, being formed with a plurality of 10 longitudinal slots 27, there being teeth 28 struck up from the body portion of the guard and disposed inwardly. In this construction it will be noted that while the removal of the packing is prevented, access to 15 the box may be had for the purpose of supplying oil thereto and for inspection.

In Fig. 5 the guard 29, which is formed integral with the plate 14, consists of a plurality of spaced bars 30, the edges of which 20 are formed with teeth 31 which are disposed inwardly, the base 32 that connects said bars also being curved inwardly and provided with teeth.

The many advantages of a construction 25 of this character will be clearly apparent, as it will be noted that it prevents the removal of the packing by unauthorized persons, it being impossible to remove the packing unless the car is lifted and the guard member removed. It will also be noted that the device is such as may be easily and economically manufactured, and that the various parts may be readily assembled.

What I claim is:—

- 35 1. A packing guard for the journal boxes of railroad cars comprising a member disposed within the journal box and interposed between the packing which is arranged in the box and the opening in the box, and a projection formed on the member and adapted to be inserted between the wedge of the journal box and the top of the box, the member being formed with openings whereby oil may be applied to the packing.
- 40 2. A packing guard for the journal boxes of railroad cars comprising a member inter-

posed between the packing which is arranged in the journal box and the opening of the box, said member including a curved toothed portion disposed to extend beneath 50 the journal, said member including an extension disposed between the wedge of the journal box and the top of the box whereby it may be maintained against displacement by the weight of the car on the box. 55

3. A packing guard for the journal boxes of railroad cars comprising a plate having an extension disposed to be inserted between the wedge of the journal box and the top of the box whereby it may be supported 60 against removal by the weight of the car on the box, a guard formed integral with said plate, said guard including spaced members the edges of which are provided with teeth, and an edge member connecting 65 the first-mentioned members and curved inwardly beneath the end of the journal, the edge of said member being toothed.

4. A packing guard for the journal boxes of railroad cars comprising a plate disposed 70 to be inserted between the wedge of the journal box and the top of the box, a second plate disposed at right angles to the first-mentioned plate and interposed between the packing and the opening of the box, said 75 plate being formed with openings.

5. A packing guard for the journal boxes of railroad cars comprising a plate disposed to be inserted between the wedge of the journal box and the top of the box, a second 80 plate disposed at right angles to the first-mentioned plate and interposed between the packing and the opening of the box, said plate being formed with openings, and a curved extension disposed beneath the 85 journal.

In testimony whereof I affix my signature in presence of two witnesses.

NATHANIEL J. ROGERS. [L.S.]
